DESIGN FOR A CHANGE PURSE

Bertie Rohr Thornhill, Lynchburg, Va.

Application December 31, 1940, Serial No. 97,746

Term of patent 3½ years

To all whom it may concern:

Be it known that I, Bertie Rohr Thornhill, a citizen of the United States of America, residing in Lynchburg, county of Campbell, and State of Virginia, have invented a new, original, and ornamental Design for a Change Purse, of which the following is a specification, reference being had to the accompanying drawing, forming part thereof, wherein,

I claim:

The ornamental design for a change purse, substantially as shown.

BERTIE ROHR THORNHILL.
